ABSTRACT

A router unit with an antenna includes a router and an antenna structure. The antenna structure is mounted in a vehicle, and includes a dielectric body with a dielectric property and a planar element with a conductive property that is provided to the dielectric body. The router includes a transferring unit and a housing. The transferring unit transfers a signal to a transfer destination. The housing houses the transferring unit and includes a shield part with a conductive property for blocking noise that affects the transferring unit. The antenna structure is provided to the shield part, connected to the transferring unit, and transmits or receives a radio wave by using the shield part as a ground of the antenna structure.

FIG.1

FIG.2

FIG.3

FIG.4

ANTENNA DEVICE AND ROUTER UNIT WITH ANTENNA

CROSS-REFERENCE TO RELATED APPLICATION(S)

The present application claims priority to and incorporates by reference the entire contents of Japanese Patent Application No. 2019-012741 filed in Japan on Jan. 29, 2019.

BACKGROUND OF THE INVENTION

1. Field of the Invention

The present invention relates to an antenna device and a router unit with an antenna.

2. Description of the Related Art

One example of the conventionally known antenna devices is an antenna unit disclosed in Japanese Patent Application Laid-open No. 2018-182415. This antenna unit is mounted in a vehicle and transmits and receives a radio wave. The antenna unit includes a dielectric body formed to have a sheet shape, a planar antenna formed at a front surface of the dielectric body, and a ground formed at a rear surface of the dielectric body. The antenna unit is connected to an electronic component of the vehicle and outputs a received signal to the electronic component.

Incidentally, in the antenna unit according to Japanese Patent Application Laid-open No. 2018-182415, it has been desired that the increase in the number of components of the antenna unit is suppressed and moreover, the attenuation of a signal after being output from the antenna unit and before reaching the electronic component is suppressed.

SUMMARY OF THE INVENTION

The present invention has been made in view of the above circumstances, and an object is to provide an antenna device and a router unit with an antenna in which the increase in the number of components and the attenuation of a signal can be suppressed.

In order to solve the above mentioned problem and achieve the object, an antenna device according to one aspect of the present invention includes an antenna structure that is mounted in a vehicle, and includes a dielectric body with a dielectric property and an antenna element with a conductive property that is provided to the dielectric body, wherein in a router including a transferring unit that transfers a signal to a transfer destination and a housing that houses the transferring unit and includes a shield part with a conductive property for blocking noise that affects the transferring unit, the antenna structure is provided to the shield part, connected to the transferring unit, and transmits or receives a radio wave by using the shield part as a ground of the antenna structure.

According to another aspect of the present invention, in the antenna device, it is preferable that the antenna structure transmits the signal, which is output from the transferring unit, to a communication system outside the vehicle or outputs the signal, which is received from the communication system outside the vehicle, to the transferring unit.

According to still another aspect of the present invention, in the antenna device, it is preferable that the shield part is

larger than the antenna element when viewed from a stacking direction of a pattern of the antenna element stacked on the dielectric body.

According to still another aspect of the present invention, in the antenna device, it is preferable that the dielectric body is formed to have a sheet shape, is disposed to face the shield part with a distance therebetween, and includes a bent part corresponding to one end of the dielectric body disposed to face the shield part, the one end being bent toward the shield part, the antenna element is provided to the dielectric body on a side of the shield part and includes a capacitive coupling part that is capacitively coupled with the shield part in a manner that a part of the antenna element is overlapped with the shield part through the dielectric body at the bent part, and the antenna structure transmits or receives the radio wave by using the shield part as the ground of the antenna structure.

In order to achieve the object, a router unit with an antenna according to still another aspect of the present invention includes an antenna structure that is mounted in a vehicle, and includes a dielectric body with a dielectric property and an antenna element with a conductive property that is provided to the dielectric body; and a router including a transferring unit that transfers a signal to a transfer destination and a housing that houses the transferring unit and includes a shield part with a conductive property for blocking noise that affects the transferring unit, wherein the antenna structure is provided to the shield part, connected to the transferring unit, and transmits or receives a radio wave by using the shield part as a ground of the antenna structure.

The above and other objects, features, advantages and technical and industrial significance of this invention will be better understood by reading the following detailed description of presently preferred embodiments of the invention, when considered in connection with the accompanying drawings.

BRIEF DESCRIPTION OF THE DRAWINGS

FIG. 1 is a schematic view illustrating an example in which a router unit with an antenna according to one embodiment is mounted;

FIG. 2 is a perspective view illustrating a structure example of the router unit with the antenna according to the embodiment;

FIG. 3 is a perspective view illustrating an example in which an antenna structure and a transferring unit according to the embodiment are connected; and

FIG. 4 is a perspective view illustrating a structure example of a router unit with an antenna according to a modification of the embodiment.

DETAILED DESCRIPTION OF THE PREFERRED EMBODIMENTS

A mode for carrying out the present invention (embodiment) is described in detail with reference to the drawings. However, the present invention is not limited by the content described in the embodiment below. In addition, the component described below includes the component that is easily conceived by a person skilled in the art or that is substantially the same. Furthermore, the structures described below can be combined with each other. Moreover, the structures can be omitted, replaced, or changed variously within the range not departing from the scope of the present invention.

3
EMBODIMENT

A router unit **1** with an antenna and an antenna device **2** according to an embodiment are described with reference to the drawings. FIG. 1 is a schematic view illustrating an example in which the router unit **1** with the antenna according to the embodiment is mounted. FIG. 2 is a perspective view illustrating a structure example of the router unit **1** with the antenna according to the embodiment. FIG. 3 is a perspective view illustrating an example in which an antenna structure **20** and a transferring unit **11** according to the embodiment are connected.

The router unit **1** with the antenna has a function of transmitting or receiving a signal, and a function of transferring the signal. The router unit **1** with the antenna is mounted in a vehicle **100**, and in this example, placed in a rear spoiler **100a** of the vehicle **100** as illustrated in FIG. 1. The router unit **1** with the antenna is housed in an internal space of the rear spoiler **100a** and fixed thereto, for example. Note that the position of the router unit **1** with the antenna is not limited to the rear spoiler **100a** and may be at any place in the vehicle **100** where the transmission and reception of a radio wave are possible.

The router unit **1** with the antenna includes a router **10** and the antenna structure **20** as illustrated in FIG. 2 and FIG. 3. The router **10** transfers a signal to a transfer destination. The router **10** includes the transferring unit **11** and a housing **12**. The transferring unit **11** is housed in an internal space of the housing **12**, and is connected to a planar element **22** of the antenna structure **20** and an electronic device in the vehicle as will be described below. The transferring unit **11** includes a routing table where the transfer destination is written, and on the basis of the routing table, transfers the signal, which is output from the planar element **22** of the antenna structure **20**, to the electronic device in the vehicle. Moreover, the transferring unit **11** transfers the signal, which is output from the electronic device in the vehicle, to the planar element **22** on the basis of the routing table.

The housing **12** houses the transferring unit **11**. The housing **12** includes a plurality of (for example, six) wall parts **12a** and is formed to have a box-like shape. Each wall part **12a** is formed to have a flat plate shape and each pair of wall parts **12a** is disposed to face each other; thus, the box-like shape is formed. The housing **12** includes the internal space for housing the transferring unit **11** therein.

Each wall part **12a** of the housing **12** includes a main body part **12b** formed to have a plate shape by an insulating member such as resin, and a shield part **12c** with a conductive property for blocking noise that affects the transferring unit **11**. The shield part **12c** is formed by, for example, providing a conductive metal plate to an external wall surface of the main body part **12b**. The conductive metal plate is formed in the entire area of the external wall surface of each main body part **12b**, and provided to each of all the six wall parts **12a**. Note that the conductive metal plate may be provided to a part of the six wall parts **12a**. The shield part **12c** is not limited to the aforementioned structure and may employ another structure. In the shield part **12c**, for example, each main body part **12b** itself may be formed by a conductive metal plate. The shield part **12c** is larger than the planar element **22** when viewed from a stacking direction of the pattern of the planar element **22** stacked on a dielectric body **21**, the stacking direction being described later. That is to say, the shield part **12c** includes an overlapping part that overlaps with the planar element **22** and an extension part that is extended outward from the overlapping part, when viewed from the stacking direction.

4

The antenna structure **20** includes the dielectric body **21** and the planar element **22** as an antenna element. The dielectric body **21** has the dielectric property, is stacked on the surface of the shield part **12c**, and is formed to have a flat plate shape. The planar element **22** has the conductive property, is stacked on the side of the dielectric body **21** opposite to the shield part **12c**, and is formed to have a thin film shape. The planar element **22** has, for example, a rectangular shape but the shape is not limited to the rectangular shape. The planar element **22** is connected to the transferring unit **11** of the router **10** through a connector cable **23**.

The antenna structure **20** transmits or receives a radio wave (signal) by using the shield part **12c** as a ground of the antenna structure **20**. The antenna structure **20** transmits the signal output from the router **10**, for example, to a communication system **101** outside the vehicle. In addition, the antenna structure **20** receives the signal from the communication system **101** outside the vehicle and outputs the received signal to the router **10**.

As described above, the router unit **1** with the antenna according to the embodiment includes the router **10** and the antenna structure **20**. The antenna structure **20** is mounted in the vehicle **100** and includes the dielectric body **21** with the dielectric property and the planar element **22** with the conductive property that is provided to the dielectric body **21**. The router **10** includes the transferring unit **11** and the housing **12**. The transferring unit **11** transfers the signal to the transfer destination. The housing **12** houses the transferring unit **11**, and includes the shield part **12c** with the conductive property for blocking the noise that affects the transferring unit **11**. The antenna structure **20** is provided to the shield part **12c** and is connected to the transferring unit **11**. Then, the antenna unit **20** transmits or receives the radio wave by using the shield part **12c** as the ground of the antenna structure **20**.

By this structure, the router unit **1** with the antenna can use the shield part **12c** of the router **10** also as the ground of the antenna structure **20**. Thus, in the router unit **1** with the antenna, the increase in the number of components can be suppressed and accordingly, the enlargement of the device can be suppressed. In addition, since the router unit **1** with the antenna includes the antenna structure **20** in the shield part **12c** of the router **10**, the distance between the router **10** and the antenna structure **20** can be made relatively short and the attenuation of the signal by the connector cable **23** between the router **10** and the antenna structure **20** can be suppressed. The router unit **1** with the antenna can relieve the antenna gain performance and suppress the enlargement of the device. Additionally, the router unit **1** with the antenna can omit a relay unit to be installed between the router **10** and the antenna structure **20**. Thus, in the router unit **1** with the antenna, the increase in the number of components is suppressed and the attenuation of the signal is suppressed, and accordingly, the enlargement of the device can be suppressed.

The antenna device **2** includes the antenna structure **20**. The antenna structure **20** is mounted in the vehicle **100** and includes the dielectric body **21** with the dielectric property and the planar element **22** with the conductive property that is provided to the dielectric body **21**. In the router **10** including the transferring unit **11** that transfers the signal to the transfer destination and the housing **12** that houses the transferring unit **11** and includes the shield part **12c** with the conductive property for blocking the noise that affects the transferring unit **11**, the antenna structure **20** is provided to the shield part **12c**, connected to the transferring unit **11**, and

transmits or receives the radio wave by using the shield part 12c as the ground of the antenna structure 20. By this structure, the antenna device 2 obtains the effect similar to that of the router unit 1 with the antenna.

In the antenna device 2, the antenna structure 20 transmits the signal output from the transferring unit 11 to the communication system 101 outside the vehicle, or outputs the signal received from the communication system 101 outside the vehicle to the transferring unit 11. By this structure, the antenna device 2 can communicate with the outside of the vehicle 100.

In the antenna device 2, the shield part 12c is larger than the planar element 22 when viewed from the stacking direction of the pattern of the planar element 22 stacked on the dielectric body 21. By this structure, the antenna device 2 can secure the antenna gain as appropriate.

Modification

Next, a modification of the embodiment is described. In the modification below, the component equivalent to that of the embodiment is denoted by the same reference sign and the detailed description of the corresponding component is omitted. FIG. 4 is a perspective view illustrating a structure example of a router unit 1A with an antenna according to the modification of the embodiment. The router unit 1A with the antenna is different from the router unit 1 with the antenna according to the embodiment in that the router unit 1A includes a monopolar element 22A instead of the planar element 22.

The router unit 1A with the antenna (antenna device 2A) includes the router 10 and an antenna structure 20A as illustrated in FIG. 4. The antenna structure 20A includes a dielectric body 21A and the monopolar element 22A as the antenna element.

The dielectric body 21A is formed to have a sheet shape, and is disposed to face the shield part 12c of the router 10 with a distance therebetween in the stacking direction. Then, the dielectric body 21A includes a bent part 21a corresponding to one end of the dielectric body 21A that is bent toward the shield part 12c. Between the dielectric body 21A and the shield part 12c, a supporting member (not shown) such as a foamed material with a dielectric property is provided. The supporting member supports the dielectric body 21A, and maintains the gap between the dielectric body 21A and the shield part 12c constant.

The monopolar element 22A has the conductive property, is stacked on the shield part 12c side of the dielectric body 21A, and is formed to have a thin film shape. That is to say, the monopolar element 22A is provided to the dielectric body 21A on a side (inner side) that faces the shield part 12c. The monopolar element 22A is connected to the transferring unit 11 of the router 10 through a connector cable (not shown). The monopolar element 22A includes a capacitive coupling part 22a that is capacitively coupled with the shield part 12c in a manner that a part of the monopolar element 22A is overlapped with the shield part 12c through the dielectric body 21A at the bent part 21a. The antenna structure 20A transmits or receives the radio wave by using the shield part 12c as the ground of the antenna structure 20A.

As described above, in the router unit 1A with the antenna (antenna device 2A), the dielectric body 21A is formed to have the sheet shape, is disposed to face the shield part 12c with a distance therebetween, and includes the bent part 21a corresponding to one end of the dielectric body 21A disposed to face the shield part 12c, the one end being bent toward the shield part 12c. The monopolar element 22A is provided to the dielectric body 21A on the side of the shield

part 12c and includes the capacitive coupling part 22a that is capacitively coupled with the shield part 12c in a manner that a part of the monopolar element 22A is overlapped with the shield part 12c through the dielectric body 21A at the bent part 21a. The antenna structure 20A transmits or receives the radio wave by using the shield part 12c as the ground of the antenna structure 20A. By this structure, the router unit 1A with the antenna (antenna device 2A) obtains the effect similar to that of the router unit 1 with the antenna (antenna device 2) according to the embodiment.

In the above example, the antenna structure 20 transmits the signal, which is output from the transferring unit 11, to the communication system 101 outside the vehicle or outputs the signal, which is received from the communication system 101 outside the vehicle, to the transferring unit 11; however, the present invention is not limited to this example. The antenna structure 20 may transmit the signal, which is output from the transferring unit 11, to a communication unit inside the vehicle or output the signal, which is received from the communication unit inside the vehicle, to the transferring unit 11.

The planar element 22 and the monopolar element 22A are described as the antenna elements; however, the antenna element is not limited to the aforementioned element and may be an antenna with another shape.

The antenna structure 20 includes one planar element 22 and the antenna structure 20A includes one monopolar element 22A; however, the number of elements is not limited to this number and each of the antenna structures 20 and 20A may include a plurality of, and a plurality of kinds of antenna elements.

In the antenna device and the router unit with the antenna according to the embodiment, the increase in the number of components can be suppressed and the attenuation of the signal can be suppressed by the use of the shield part of the router as the ground of the antenna structure.

Although the invention has been described with respect to specific embodiments for a complete and clear disclosure, the appended claims are not to be thus limited but are to be construed as embodying all modifications and alternative constructions that may occur to one skilled in the art that fairly fall within the basic teaching herein set forth.

What is claimed is:

1. An antenna device, comprising:
an antenna structure that is mounted in a vehicle, and includes a dielectric body with a dielectric property and an antenna element with a conductive property that is provided to the dielectric body, wherein

in a router including a transferring unit that transfers a signal to a transfer destination and a housing that houses the transferring unit and includes a shield part with a conductive property for blocking noise that affects the transferring unit, the antenna structure is provided to the shield part, connected to the transferring unit, and transmits or receives a radio wave by using the shield part as a ground of the antenna structure,

the dielectric body is formed to have a sheet shape, is disposed to face the shield part with a distance therebetween, and includes a bent part corresponding to one end of the dielectric body disposed to face the shield part, the one end being bent toward the shield part,

the antenna element is provided to the dielectric body on a side of the shield part and includes a capacitive coupling part that is capacitively coupled with the shield part in a manner that a part of the antenna

element is overlapped with the shield part through the dielectric body at the bent part, and the antenna structure transmits or receives the radio wave by using the shield part as the ground of the antenna structure.

2. The antenna device according to claim 1, wherein the antenna structure transmits the signal, which is output from the transferring unit, to a communication system outside the vehicle or outputs the signal, which is received from the communication system outside the vehicle, to the transferring unit.

3. The antenna device according to claim 2, wherein the shield part is larger than the antenna element when viewed from a stacking direction of a pattern of the antenna element stacked on the dielectric body.

4. The antenna device according to claim 1, wherein the shield part is larger than the antenna element when viewed from a stacking direction of a pattern of the antenna element stacked on the dielectric body.

5. A router unit with an antenna, comprising: an antenna structure that is mounted in a vehicle, and includes a dielectric body with a dielectric property and an antenna element with a conductive property that is provided to the dielectric body; and

5

10

15

20

a router including a transferring unit that transfers a signal to a transfer destination and a housing that houses the transferring unit and includes a shield part with a conductive property for blocking noise that affects the transferring unit, wherein

the antenna structure is provided to the shield part, connected to the transferring unit, and transmits or receives a radio wave by using the shield part as a ground of the antenna structure,

the dielectric body is formed to have a sheet shape, is disposed to face the shield part with a distance therebetween, and includes a bent part corresponding to one end of the dielectric body disposed to face the shield part, the one end being bent toward the shield part,

the antenna element is provided to the dielectric body on a side of the shield part and includes a capacitive coupling part that is capacitively coupled with the shield part in a manner that a part of the antenna element is overlapped with the shield part through the dielectric body at the bent part, and

the antenna structure transmits or receives the radio wave by using the shield part as the ground of the antenna structure.
